UNITED STATES PATENT OFFICE.

ROSS ARMSTRONG, OF ONAWA, IOWA.

MAGIC TOY.

SPECIFICATION forming part of Letters Patent No. 513,450, dated January 23, 1894.

Application filed May 16, 1893. Serial No. 474,407. (No model.)

To all whom it may concern:

Be it known that I, ROSS ARMSTRONG, of Onawa, in the county of Monona and State of Iowa, have invented a new Improved Magic 5 Toy, of which the following is a full, clear, and exact description.

The object of the invention is to provide a new and improved magic toy, which is simple and durable in construction, affords considerable amusement, and is arranged to magically illustrate the coining of money from blanks.

The invention consists of a die in the form of a drop bottom adapted to receive the blank, 15 and a coin receptacle operating over the said die and adapted to trip the latter to remove the blank and to deposit a coin thereon.

The invention also consists of certain parts and details, and combinations of the same, as 20 will be hereinafter described and then pointed out in the claims.

Reference is to be had to the accompanying drawings, forming a part of this specification, in which similar letters of reference indicate 25 corresponding parts in both the figures.

Figure 1 is a sectional side elevation of the improvement on the line 1—1 of Fig. 2; and Fig. 2 is a sectional plan view of the same on the line 2—2 of Fig. 1.

30 The improved toy is provided with a suitably-constructed casing A, closed on top by a lid A', formed in its middle with a circular opening A², into which fits a similarly shaped die B, forming a drop bottom and hinged at 35 its lower end at B' to the under side of the cover or lid A'. The top of the die B is adapted to receive a blank C, as illustrated in the drawings.

The under side of the die B opposite the 40 pivot B' is adapted to be supported by a spring plate D, guided in suitable bearings A³, arranged on the under side of the lid or cover A'. The plate D is adapted to be engaged, to withdraw it from under the die B, by a wedge-shaped notch E' formed on the 45 lower end of a post E, mounted to slide vertically in suitable guideways F arranged within the casing A. A second post E², arranged parallel to the post E is mounted to slide in 50 a guideway F' also arranged within the cas-

ing, the upper ends of the said posts E and E² being connected with each other by a cross bar E³, and on the said posts are coiled springs E⁴, resting with their lower ends on the top of the cover A', and pressing with their upper ends against the under side of the cross bar E³. The said posts, cross bar and springs form a sliding frame for the coin receptacle G, secured to the under side of the cross bar E³, and adapted to support the coins H, placed 60 one on top of the other and held in place in the lower open end of the said receptacle by an internal annular flange G', formed in the lower end of the said receptacle G. A tripping arm or lever I, engages the edge of the 65 lowermost coin so as to push the latter off the flange G' into the opening therein, to permit the said coin to pass through the lower end of the receptacle G onto the die B after the blank C is removed, and at the time the receptacle G moves downward onto the top of the cover A' as hereinafter more fully described.

The lever I, is pivoted on the inside of a sleeve J, surrounding the lower end of the 75 receptacle G, and supported on springs K, attached to the under side of the cross bar E³. A spring L, presses on the uppermost coin within the receptacle G so as to hold the same in place on the flange G' of the receptacle G. 80 The die B is provided on its pivot end with an extension B², pressed on by a spring B³, secured to the under side of the cover A', so as to hold the said die in a normal position in the opening A². The said extension B² is 85 also engaged by a tripping lever N, fulcrumed on the under side of the cover A' and adapted to be engaged by a lug E⁵, formed on the post E³, as plainly illustrated in Fig. 1. A spring N', presses against the under side of the tripping lever so as to hold the latter in a normal 90 position, that is, in contact with the extension B².

On top of the cover A' and near the edge of the aperture A² is arranged a series of lugs 95 O, one of which is adapted to be engaged by the lower free end of the lever I at the time the receptacle G is moved downward, so as to actuate the said lever I to shift the lowermost coin into the opening of the annular flange 100

G'. In the covering A directly below the die B is arranged a receptacle P, preferably lined with a soft material and adapted to receive the blank sliding off of the die B, when the latter swings downward into an inclined position. The lining within the receptacle P deadens the noise of the falling blank.

The operation is as follows: The coin receptacle G is filled with a number of coins, 10 say dimes, of which the lowermost is supported on the annular flange G', it being understood that the opening of the latter is larger in diameter than the coins H supported on one side of the flange. Now, when the 15 several parts are in position, as illustrated in Fig. 1, then the operator places a blank C, preferably of lead onto the die B and then presses a knob E⁶, on the top of the cross bar E³, so as to cause the posts E and E², the cross 20 bar E³ and the coin receptacle G suspended on the latter, to move downward, whereby the projecting sleeve J on the lower end of the coin receptacle G first engages the top of the cover A' to close over the blank C. At this time the 25 lug E⁵ moves in contact with the tripping lever N, so that the latter receives a swinging motion and imparts a like downward swinging motion to the die B, to permit the blank C to slide off the die down into the receptacle 30 P. It is understood that the die B is unlocked soon after the downward movement of the bar E³ begins, as the wedge E', acting on the spring plate D, moves the latter outward from under the said die B. On a farther downward 35 movement of the cross bar E³, after the sleeve J is in contact with the cover A', the said sleeve commences to slide upward, so that finally the lower end of the lever I, moves in contact with the corresponding lug O, 40 whereby a swinging motion is given to the said arm I and the lowermost coin H is shifted into the opening of the flange G' and consequently drops through the said opening onto the top of the die B. The latter has returned 45 to its normal position previous to the depositing of the lowermost coin, as the lug E⁵ has then passed the tripping lever N, and the spring N' thereof has returned the latter to its normal position to permit the spring B³ to 50 return the die to its normal position. When the operator then releases the pressure on the knob E⁶, the springs E⁴ return the posts E, E², the cross bar E³ and receptacle G and the sleeve J to their normal positions, as illustrated 55 in Fig. 1, so that a coin now appears on the die B, while the blank has disappeared from the latter, thus leaving the impression that a coin has been manufactured.

It is understood that when the cross bar E³ 60 commences to move upward on the release of the pressure on the knob E⁶, then the sleeve J slides downward back to its normal position on the receptacle G, by the action of the springs K supporting the said sleeve. In doing so, the lever I engages the next coin 65 pressed down by the spring L in the receptacle G. The above described operation may

then be repeated, that is, a blank is first placed on the die B, then pressure is given on the knob E⁶, to cause a downward sliding of 70 the several parts, and the disappearing of the blank from the die B and the depositing thereon of the lowermost coin from the receptacle G.

It will be seen that the magic toy is very 75 simple in construction and affords considerable amusement.

Having thus fully described my invention, I claim as new and desire to secure by Letters Patent—

1. A magic toy comprising a die in the form of a drop bottom and adapted to receive the blank, and a coin-receptacle operating over the said die, and adapted to trip the same to remove the blank and then to deposit a coin 85 thereon, substantially as shown and described.

2. A magic toy comprising a receptacle, a die in the form of a trip bottom arranged in the top of the said receptacle, a coin receptacle adapted to operate over the said die, and supported on a spring-pressed frame, and a tripping lever actuated by the said frame to trip the said die to cause the blank thereon to slide into its receptacle, substantially as 95 shown and described.

3. A magic toy comprising a receptacle, a die in the form of a trip bottom arranged in the top of the said receptacle, a coin receptacle adapted to operate over the said die, and supported on a spring-pressed frame, a tripping lever actuated by the said frame to trip the said die, to cause the blank thereon to slide into its receptacle, and a tripping arm arranged in the said coin receptacle to trip 105 the lowermost coin therein at the time the coin receptacle nears the top of the blank receptacle, substantially as shown and described.

4. A magic toy comprising a receptacle, a 110 die in the form of a trip bottom arranged in the top of the said receptacle, a coin receptacle adapted to operate over the said die and supported on a spring-pressed frame, a tripping lever actuated by the said frame to trip 115 the said die to cause the blank thereon to slide into its receptacle, and a spring plate engaging the free end of the said die to lock the latter in a normal position, substantially as shown and described.

5. A magic toy comprising a receptacle, a die in the form of a trip bottom arranged in the top of the said receptacle, a coin receptacle adapted to operate over the said die and supported on a spring-pressed frame, a tripping lever actuated by the said frame to trip the said die to cause the blank thereon to slide into its receptacle, a spring plate engaging the free end of the said die to lock the latter in a normal position, and means, substantially as described, for withdrawing the said spring plate previous to actuating the said tripping lever, substantially as shown and described.

6. A magic toy, comprising a coin receptacle formed at its lower end with an annular flange, a sleeve mounted to slide on the lower end of the said receptacle, springs engaging the said sleeve, and a tripping arm pivoted in the said sleeve and adapted to engage the lowermost coin in the said receptacle, to move the said coin off the said flange into the opening thereof, at the time the sleeve moves upward, substantially as shown and described. ¹⁰
